DESIGN FOR AN ENVELOPE BLANK

Vera Bock, New York, N. Y., assignor to United States Envelope Company, Springfield, Mass., a corporation of Maine

Application November 27, 1944, Serial No. 116,575

Term of patent 14 years

(Cl. D59—8)

To all whom it may concern:

Be it known that I, Vera Bock, a citizen of the United States, residing at New York, in the county of New York and State of New York, have invented a new, original, and ornamental Design for an Envelope Blank, of which the following is a specification, reference being had to the accompanying drawing, forming part thereof, in

which the figure is an inside plan view of an envelope blank, showing my new design, the opposite side being plain.

I claim:

The ornamental design for an envelope blank, as shown and described.

VERA BOCK.
